UNITED STATES PATENT OFFICE.

HARRY HAMILTON, OF LEBANON, INDIANA.

DOUBLE-ACTING PUMP.

1,240,712.

Specification of Letters Patent. Patented Sept. 18, 1917.

Application filed July 30, 1914. Serial No. 854,037.

To all whom it may concern:

Be it known that I, HARRY HAMILTON, a citizen of the United States, and a resident of the city of Lebanon, county of Boone, and State of Indiana; have invented certain new and useful Improvements in Double-Acting Pumps, of which the following is a specification.

My invention relates to improvements in double-acting pumps designed for use especially in the pumping of water, and has for its object the production of a pump of this character which will be of improved construction and efficient in operation. Other objects will appear hereinafter.

The invention consists in the combinations and arrangements of parts hereinafter described and claimed.

The invention will be best understood by reference to the accompanying drawings forming a part of this specification, and in which,

Figure 1 is a central vertical section of a pump embodying my invention,

Figs. 2 and 3 are perspective views of parts of the pump detached, and

Figs. 4 and 5 are enlarged transverse sections taken on lines *x—x* and *y—y* respectively of Fig. 1.

The preferred form of construction as illustrated in the drawings comprises a cylindrical wall 1 in the ends of which are threaded caps 2 and 3 formed at their outer ends with inlet and outlet ports 4 and 5 respectively. Arranged in the ends of member 1 are circular plates or transverse partitions 6 and 7 which engage against annular shoulders formed in said ends and locked in position by engagement therewith of the end members 2 and 3.

Arranged centrally in the member 1 is a cylinder 8 at the ends of which are arranged heads 9 and 10, said heads being held rigid in operative position by webs 11 and 12 formed integral with and inwardly projecting from the plates 6 and 7 respectively.

Mounted for reciprocation in cylinder 8 is a piston 13 which is connected with the lower end of a rod 14, the latter projecting upwardly through the head 10, web 12 and plate 7 which serve as a bearing therefor, a suitable packing surrounding said stem at the upper side of plate 7 to prevent leakage. In use, the stem 14 extends upwardly to the surface of the ground where the same

is connected with suitable mechanism for imparting reciprocatory movement thereto, as will be readily understood.

The members 1 and 8 are relatively of such dimensions as to result in the formation of an annular space between the same, this space being divided by the webs 11 and 12 and longitudinally extending diametric partitions 15 which extend between the adjacent or inner edges of said webs into independent chambers 16 and 17. The plate 6 is provided with openings 18 and 19 which communicate respectively with the lower ends of chambers 16 and 17, and the plate 7 is provided with openings 20 and 21 communicating respectively with the upper ends of said chambers. The openings 18, 19, 20 and 21 are governed by flap valves 18', 19', 20' and 21' respectively, each of said valves comprising a flexible body formed of rubber, leather or other suitable material which is secured in position at one edge by a screw or other suitable fastening 22, a reinforcing plate 23 being secured to the upper side of each of said valves.

The head 10 at the upper end of cylinder 8 is cut away at one side as at 24 to establish open communication between said end of said cylinder and the chamber 16, the plate 9 being correspondingly cut away at 25 in order to establish open communication between the lower end of said cylinder and the chamber 17.

With a construction as set forth, it will be seen that upon downward movement of the piston 13, (assuming the latter to be at its upper terminal of movement) a suction will be created in the upper end of cylinder 8 and consequently in the chamber 16 which will cause the valve 20' to be drawn tightly to its seat or closing position, and the valve 18' to be flexed upwardly to open position, in order to allow for the entrance of water from the inlet port 4 which will be drawn up into chamber 16 and the upper end of chamber 8 by reason of the suction created. Upon the return movement of said piston, the water thus drawn into chamber 16 and the upper end of cylinder 8 will be forced by said piston upwardly through the valve 20' which will be moved to open position by the pressure of the water against the under side thereof, the valve 18' being simultaneously moved to closing position by reason of the pressure of the water at the upper side thereof. At the same time, this upward

movement of piston 13 will tend to create a vacuum in the lower end of cylinder 10 and the chamber 17 which will effect closing of valve 21' and opening of valve 19', the valve 19' permitting of the passage of water into chamber 17 and the lower end of cylinder 9, the water being drawn thereinto by reason of the suction created through the partial vacuum formed, as is readily understood. Upon the return or downward movement of piston 13 the water thus drawn upwardly into chamber 17, and the lower end of cylinder 8, will be forced upwardly through valve 21' which will be opened by reason of the pressure against the under side thereof, the valve 19' being moved to closing position by this pressure. During the downward movement of the piston the same action as first described with regard to chamber 16 and the upper end of cylinder 8 will take place. Thus, it will be seen that a double-acting pump is provided, that is, one in which water is elevated during both strokes of the piston.

The arrangement is simple and economical in construction and hence may be manufactured at a low cost, and will be found highly efficient in operation.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and

modifications as come within the scope of the appended claim.

Having described my invention what I claim as new and desire to secure by Letters Patent is:

In a device of the kind described, in combination an outer and an inner cylinder, circular plates supported against the opposite ends of said outer cylinder, and having valve controlled ports, a centrally formed diametrical web on each circular plate, the central portion of one web providing a sleeve, semi-circular heads formed at right angles upon each web, the inner cylinder being of such length and diameter as to engage the inner sides of said semi-circular heads so as to be supported against vertical displacement within the outer cylinder, a pair of longitudinally disposed partitions secured upon the inner side of said outer cylinder at diametrically opposite points therein and having concave faces, said inner cylinder engaging the concave faces of said partitions so as to be held against displacement and be positioned concentrically in the outer cylinder, a piston moving in said inner cylinder and a piston rod secured to said piston and projecting through said sleeve.

In testimony whereof I have signed my name to this specification in the presence of two subscribing witnesses.

HARRY HAMILTON.
